UNITED STATES PATENT OFFICE.

HIRAM CULVIN REYNOLDS, OF GREENFIELD, IOWA.

AUTOMATIC GATE FOR RAILROADS.

SPECIFICATION forming part of Letters Patent No. 308,196, dated November 18, 1884.

Application filed May 12, 1884. (No model.)

To all whom it may concern:

Be it known that I, H. C. REYNOLDS, of Greenfield, in the county of Adair and State of Iowa, have invented an Automatic Gate for 5 Railroads, of which the following is a specification.

The object of the invention is to enable the railroad-trains to automatically open and close the gates which cross their tracks.

10 The invention consists in the means by which this is accomplished, and which will be hereinafter particularly described, and pointed out in the claims.

Figure 1 of the drawings is a perspective 15 view showing the cross-gate shut. Fig. 2 is a perspective view showing the gate open for the train to pass. Fig. 3 is a vertical section of the elevated post, with the air-tube, plunger, and pulleys, together with the rope or 20 flexible connection by which the gate is raised. Fig. 4 is a detail view showing the grooved track-rail in section and the air-reservoir partly in section, with the piston connected by its rod with the under side of the middle 25 of the spring.

In the drawings, A A' represent two posts rigidly fixed in and on opposite sides of a sleeper or cross-tie, which passes under the track G of the railroad.

30 B is an upright connected with the more elevated post A by bars C. The latter are arranged in pairs pivoted to the outside of both the post A and the upright B, so that the parts B C may fold up into a vertical position, as shown in Fig. 2 of the drawings. The post A is hollow, and provided with a plunger, D, which is movable up and down in a tube, I, in the post-cavity. This plunger is connected at its lower end with a wire rope, E, 40 (or equivalent device,) which passes over pulleys d d, journaled in the post near the top and bottom of its cavity to a cross-pin, c', between the two topmost gate-bars, C C. Thus it will be seen that if the plunger D is forced 45 up the gate itself is also raised and folded back for the train to pass.

F F represent air-tanks on opposite sides of the gate, each provided with a piston, f, whose rod f' extends up through the track- 50 rail G, and is attached to or pressed against

the under side of the middle of the bow-spring H, which is secured so that its ends will slide in slots g g of the rail, and thus allow the plate to straighten out as the pressure of the car-wheels come upon it. The effect of this 55 is to force down the piston f and expel the air from the tank.

I I represent pipes or tubes, which connect the air-tanks F F with the post-cavity in which the plunger D works, so that as the air 60 is forced from either of the tanks into the cavity of the post A and against the bottom end of the plunger D the latter rises and folds up the gate. As soon as the springs are allowed to rise, their tension and the back pressure of 65 the air will cause the pistons f to rise to the upper part of their cylinders. As the air now no longer supports the plunger D, the gravity of the gate will overcome that of the plunger and draw it down to the lower end of 70 the post-cavity, while the gate itself will descend to its normal position across the railroad-track.

a represents a rear weighted latch-lever, which is lifted by the rising plunger D through 75 an extension pin or lug at its upper end. This causes the latch to catch over the cross-pin c' of the gate, and thus lessen the resistance made to the air-pressure by the weight of the gate. As soon, however, as the spring 80 H is relieved from pressure and the air ceases to exert its pressure upon the bottom of plunger D, the latter sinks to the bottom of post A and the weight on the rear end of the latch unhooks it from the cross-bar c', thus allowing the gate to gradually assume its place, 85 as shown in Fig. 1 of the drawings.

In practice the operation is very certain, exact, and convenient. The presence of the locomotive effectually deters the stock from 90 attempting to pass through the gate when the latter is raised.

Having thus described all that is necessary to a full understanding of my invention, what I claim as new, and desire to protect by Letters Patent, is—

1. The combination, with a folding gate having the hinged bars C and movable upright B, of the wire rope E, hollow fixed post A, carrying pulleys d d, and a piston, D, mov- 95 too

able up and down in said post, as and for the purpose described.

2. The combination, with a folding rail-road-gate and track-rail, of a bow-spring, H, an air device, I F f', a hollow fixed post, A, and a plunger, D, connected with said gate by a wire rope passing over pulleys jour-

naled in said post, as and for the purpose specified.
